UNITED STATES PATENT OFFICE.

JOACHIM SANTOUX, OF LYON, FRANCE.

CARBURETOR.

Application filed June 25, 1920. Serial No. 391,641.

To all whom it may concern:

Be it known that I, JOACHIM SANTOUX, a citizen of the Helvetic Republic, residing at Lyon, France, have invented new and useful 5 Improvements in Carburetors, of which the following is a specification.

This invention relates to carburetors principally intended for use in internal combustion engines, the main object of the 10 invention being to provide a device in which the degree of vacuum on the spraying nozzle is variable and adjustable so that the carburetor will automatically adjust itself to the requirements of the full range of the 15 engine speeds. This result is obtained by automatically varying the cross-sectional area of the intake passage adjacent the nozzle. This variation may be accomplished by various means, the simplest means being 20 to provide in the intake passage a square or rectangular cross section, and to locate in this passage two shutters diametrically opposed and each of said shutters being connected to a spindle at its base, which spindle 25 is located perpendicular to the axis of the spraying-nozzle.

The shutters are provided at their upper edges with notches which, when the shutters are in closed position, form a small passageway 30 between the shutters. This passageway prevents the passage to the engine intake of a small quantity of air and fuel mixture for idling or starting purposes.

As the throttle is opened the opening between the shutters is progressively increased 35 and the intake passage proportionately enlarged, thus preventing as rapid increase in vacuum at the nozzle as would otherwise occur.

40 In the drawings accompanying and forming part of this specification,

Fig. 1 is a vertical section taken at right angles to Figure 2.

Fig. 2 is a vertical section along the 45 middle longitudinal line of the body of the carburetor;

Fig. 3 is a section taken on the line B—B of Fig. 1 looking upwardly and

50 Fig. 4 is an end view of the carburetor shown in Fig. 2 showing the mechanism for operating the shutters for the air-inlet.

Similar characters of reference indicate corresponding parts throughout all figures of the drawings.

55 The upper part α in which the throttle valve p is located is of cylindrical section.

The lower part in which are located the chambers c , c' , has a peculiar form; its general section being rectangular, the vertical side walls a^4 being parallel to one another, while the side walls a^3 are so formed as to make an angle as shown in Figs. 2 and 4. The narrowed top of the sides a^3 , a^4 , of the body are united with the cylinder a and form the chamber c above the spraying nozzle and shutters. The enlarged bottom c' is open to the atmosphere as shown.

On one of the walls a^3 there is affixed the float chamber z , which is of the usual construction, the opposite wall a^3 having a projecting portion a^5 which is longitudinally bored and has located therein a helical spring r which is located on a rod j ; this spring is held within a fixed plug k screwed in the bottom of the portion a^5 , and a ring n fixed by a pin n' at the upper end of the rod j . The lower end of this rod is provided with a grooved roller m . The spring r acts to constantly push the rod upwardly in order to maintain the tip of it in permanent touch with a cam q located above the same and which cam is affixed to an extension p^a of the axle l of the throttle valve p .

The shutters v are provided with axles i , the ends of which rotate in the bottom of the side walls a^4 . These shutters are of very substantial construction, as shown in Fig. 2, in order that the transverse upper rim of each, which is cut as a bevel, may offer a broad surface v^4 as shown in Fig. 1. The lower face of both shutters is deepened so as to make up a hollow v^2 similar to the hollow of a spoon. The upper rims of the shutters are notched in the middle so as to make up the circular aperture o when the shutters are brought against each other, said aperture being then placed directly above the orifice mouth of the spraying nozzle g , as shown in Figs. 2 and 3.

One of the slanting sides a^3 has connected thereto a nipple t axially bored by an opening having two diameters y , y' , the intersection of which forms a conical shoulder for the seat of a needle valve x secured in the upper part of said opening. The smaller diameter y' opens in the upper part of the chamber c so as to admit to the chamber c the atmospheric air entering through the small opening u located in the nipple near the end of the opening y , Fig. 2.

The spindles i of the shutters v have secured thereto at one end the rods b , which

are operated by the valve p , by means of the cam q , the rod j and the roller m . To that end the free ends of said rods b are formed as a ball, and engage in the groove 5 of the roller m and are attached in such a manner that they remain in contact with said roller m no matter what may be the position of the valve and the rods b are oscillated by the to-and-fro movement of the 10 rod j .

The operation of the device is as follows: The throttle valve p , which is operated by the lever l , moves the cam q . This cam q is located directly above the rod j and bears 15 thereon, so that, according to the direction of rotation of the lever l , the cam forces downwardly the rod j and compresses the spring r , or permits the rod j to move upwardly by means of the tension of said 20 spring r . The downward movement of said rod j will tend to close the valve p , and at the same time will bring downwardly the rods b , thus bringing the shutters v towards each other, while the upward movement of 25 the rod j under tension of the spring will tend to open the valve p and at the same time force up the rods b and thus open the shutters v . It will therefore be noted that the position of the shutters v is positively 30 controlled by the position of the throttle valve p .

Supplementary air is introduced into the chamber c through the passages u and y' , and the supply of air is adjustable by means 35 of the needle valve x to form a mixture of

proper proportions for idling. This supply of air is advantageous, especially during slow running of the motor, in order to lessen the oil waste, or to diminish the proportion of oil in the mixture. This opening can be 40 entirely closed by screwing in the punch x .

It will, of course, be understood that various changes and modifications may be made to the details of construction without in any way departing from the spirit or scope of 45 the present invention.

I claim:

In a carburetor, a liquid fuel chamber, a pair of mutually separable shutters each having a notch at its upper end and forming an air intake communicating with said chamber, a throttle valve disposed in the upper portion of the carburetor, a pivoted lever connected with said valve for operating the same, a cam operatively connected to said lever, a rod normally maintained under tension in contact with said cam, a grooved roller secured at the lower end of said rod, a pair of spindles and a pair of levers each connected at one of its ends to one of said spindles, the opposite ends thereof being in contact with the grooved roller, the shutters also being pivotally connected at their lower ends to the spindles so that upon actuation of the valve the shutters will also be operated to open or close the same. 60

In testimony whereof I have signed my name to this specification.

JOACHIM SANTOUX.
